POWER SETWORK FOR SAWMILL CARRIAGES

Ulmont R. Lewis, Seattle, Wash.

Application November 12, 1947, Serial No. 785,483

7 Claims. (Cl. 143—120)

1 This invention relates to power-actuated setworks for sawmill carriages, and has for its general object the provision of an especially simple and inexpensive apparatus which is of rugged construction and which will dependably perform its intended end of advancing and retracting the log-carrying knees of a saw-carriage's head-block.

These and other more particular objects and advantages in view will appear and be understood in the course of the following description and claims, the invention consisting in the novel construction and in the adaptation and combination of parts hereinafter described and claimed.

In the accompanying drawings:

Figure 1 is a fragmentary top plan view of a sawmill carriage and illustrating a preferred embodiment of the present invention applied thereto.

Fig. 2 is a rear elevational view thereof.

Fig. 3 is a transverse vertical sectional view taken to an enlarged scale on line 3—3 of Fig. 1.

Fig. 4 is a fragmentary longitudinal vertical sectional view on line 4—4 of Fig. 1, the scale corresponding to that of Fig. 3; and

Fig. 5 is a fragmentary top plan view employing a yet larger scale and detailing the particular features which essentially constitute the improvements of the present invention.

Referring to said drawing, the numeral 10 represents a reciprocally-movable log-carriage motivated by any suitable means (not shown), and guided in its said reciprocatory movement by wheels 11 tracking upon rails 12. The framework of the carriage is indicated as being constituted of laterally spaced longitudinal girders 13—14 connected by a severality of transverse tie-beams 15, and there is provided upon opposite ends of the framework the usual transversely extending head-blocks, as 16 and 17, each of which provides a transverse slide-way for the mounting of a respective knee 18. The two knees each carry a rack 20 upon the underside thereof, and there is journaled upon the framework of the carriage and extending longitudinal to the latter a shaft 21 supporting upon its ends spur pinions 22 and 23 in mesh with the racks. A master set-shaft 24 placed transverse to the carriage drives the shaft 21 through intermeshing bevel gears 25—26. No novelty is professed to the use of the rack-and-pinion assemblies, and in lieu thereof any other of the available devices which are functional to convert rotary motion of the shaft 24 to an end-wise sliding motion of the knees 18 and such, for example, as jack-screw and nut assemblies are or may be used. The present invention is essentially

concerned with the provision of perfected means for imparting to the shaft 24 conversely directed and controlled rotary motion necessary to predeterminedly move the knees in relation to the plane of the saw (not shown) both in respect of the direction and the degree of travel.

According to the present invention, the master set-shaft 24 is caused to project rearwardly beyond the carriage and there is made fast to this projected end a winch-drum 30 formed in its perimeter with a continuous spirally-developed groove. Complementing this winch-drum and journaled beyond one end extremity of the carriage's limit of reciprocal travel is a similar winch-drum 31 likewise formed in its perimeter with a continuous spirally developed groove, and while not shown there is made fast to this second winch-drum a brake drum received in a stationary brake housing 32. The brake which I employ is desirably of the hydraulic type, and which is to say that the shoe for the drum is activated by energy derived from a piston working in a hydraulic cylinder, and the pressure fluid is fed to such cylinder through a hose 33 wrapped by its delivery end upon a spring-wound reel 34 and having its other end connected by a suitable coupling 35 with a pipe 36 fixedly attached to the carriage, this pipe leading from a control cylinder 37 mounted upon an operator's platform 38. A foot-operated button 39 actuates a plunger received in this cylinder.

At the other extreme of the carriage's end limit of reciprocal travel, the invention provides a pulley 40 journal-mounted in the furcate head of a block 41, and formed as an integral prolongation of this head is a rod 42 journaled in a bearing 43 for sliding movement along an axis longitudinal to the reciprocal travel of the carriage. The aft end of this rod is threaded, and has applied thereover a spring 44 maintained under compression, against a pull force exerted upon the pulley, by a keeper 45 and backing nut 46.

Completing my setworks assembly is an endless cable 47 which passes over the pulley and is given two or more wraps about each of the winch-drums 30 and 31, the directional course of the wraps being opposite as between the two drums and which is to say that the cable is fed to the bottom side of the winch-drum 30 from the top side of the winch-drum 31, and from the bottom side of the former passes around the pulley 40 and thence returns directly to the bottom side of the winch-drum 31. In compensation of this reverse winding, the two winch-drums are vertically offset from one another to place the lower limit of the

winch-drum 30 preferably in a horizontal plane coinciding with the upper limit of the winch-drum 31.

The operation may be described as follows: There is produced, principally by the drag load of the log-shifting knees and partly by the friction inherent to the transfer gearing, a resistance sufficient to normally brake the winch-drum 30, and assuming that the other winch-drum 31 is not braked and is hence free to rotate, a movement of the carriage will then simply localize the cable wraps upon the winch-drum 30 and cause the cable wraps upon the winch-drum 31 to turn the latter, the cable wraps then working progressively along the grooves of the drum either in one or the other axial direction according as to which direction of reciprocation the carriage is moving. Now, if it is desired to advance or retract the knees, and which is accomplished in the one instance while the carriage travels in one direction and in the other instance while the carriage travels in the opposite direction, the operator need only step on the plunger-control button and the responsive braking of the winch-drum 31 localizes the cable wraps upon the latter and the frictional grab of the cable then causes the winch-drum 30 to turn, whereupon responsive movement is transmitted through the bevel gears and the rack-and-pinion gearing to the knees, the cable being perforce held in a taut condition by the operation of the spring 44. In the lay-out as it is shown in the drawing, an advance of the knees will be made to occur by a braking of the winch-drum 31 as the carriage moves from left to right in Figs. 1 and 2, and a retraction of the knees will occur by braking the winch-drum as the carriage moves in the opposite stroke of reciprocation, and namely from right to left.

Although not illustrated in the drawing, there is provided upon the carriage a suitable scale and marker permitting the operator to accurately regulate the successive settings of the log to the cutting of any desired board thickness.

While there are presently available a number of very efficient setworks powered by electricity, this form of power is not readily available to a number of operating mills, especially those of the increasingly popular portable nature, and the present invention provides for these mills an extremely simple, inexpensive and dependable power setworks requiring a minimum of parts for its operation and eliminating the objectionable feature, which is common to substantially all prior mechanical setwork assemblies, of having clutches and shifting levers mounted upon the carriage. Over and above an increased operating cost consequent to the greater load which the carriage is required to carry when these parts, with necessary bearings, brackets and the like, are so mounted, there is the further objection that the same are usually centralized on or near the operator's platform and by interfering with the operator's freedom of movement become a hazard to the safety of the operator. It will, of course, be apparent that the present invention adapts itself equally well to a sawmill in which the operator rides the carriage or one in which the setworks are controlled from an off-carriage vantage point, the latter type of installation being, perforce, even more simplified than that which I have illustrated inasmuch as the hose-winding reel is then eliminated and a fixed length of hose run directly from the off-carriage control platform to the cylinder of the hydraulic brake.

My setworks assembly may, in either said case, be installed at low cost and inasmuch as most of the prior mechanically set carriages have a master set-shaft placed transverse to the carriage it becomes possible to easily apply the present invention to mills already in operation without making it necessary to alter the existing basic equipment.

The invention admits of minor changes in the details of construction and it is my intention that the hereto annexed claims be given a scope commensurate with the broadest interpretation which the employed language fairly permits.

What I claim is:

1. As a power setworks, and in combination with a reciprocally movable sawmill carriage having a master set-shaft journaled thereon for rotary movement about an axis at right angles to the path of movement of the carriage and providing transversely movable knees operatively inter-connected with the set-shaft to cause the knees to be advanced and retracted by oppositely directed rotation of the set-shaft, a winch-drum fast to the set-shaft, a complementary winch-drum supported for rotary movement about a stationary axis paralleling that of the first-named drum and removed to one side of the latter, a pulley removed to the other side of the first-named drum, and an endless cable having multiple wraps taken about the second-named drum and passing therefrom to and about the pulley and in its return run having multiple wraps taken about the first-named drum, means being provided for braking the second-named drum at will.
2. The setworks of claim 1 characterized in that the winch-drums are each formed in their perimeter with a continuous spirally developed groove guiding the multiple wraps of the cable and, position considered, serving to maintain a constant correlation as between the cable wraps and the knees, the overall span of said grooves compensating the wraps to an endwise movement upon the drums relatively in correspondence with the overall travel of the knees.
3. The setworks of claim 1 in which the brake is hydraulically operated, and having operating connection from the carriage to said brake.
4. As a power setworks, and in combination with a reciprocally movable sawmill carriage having a master set-shaft journaled thereon for rotary movement about a transverse horizontal axis and providing transversely movable knees powered from the set-shaft to cause the knees to be advanced and retracted by oppositely directed rotary movements of the set-shaft, said set-shaft projecting rearwardly beyond the carriage, a winch-drum fast to said rear projection of the shaft, a second winch-drum occupying a position beyond the first drum's end limit of travel in one direction of the carriage's reciprocatory movement and journaled for rotation about a stationary axis paralleling the rotary axis of the first drum, means for braking said second drum at will, a pulley supported to occupy a position beyond the first drum's end limit of travel in the other direction of the carriage's reciprocatory movement, and an endless cable having multiple wraps taken about the second drum and passing therefrom to and about the pulley and in its return run having multiple wraps taken about the first drum.
5. As a power setworks, and in combination with a reciprocally movable sawmill carriage having a master set-shaft journaled thereon for rotary movement about a transverse horizontal

5

axis and providing transversely movable knees powered from the set-shaft to cause the knees to be advanced and retracted by oppositely directed rotary movements of the set-shaft, said set-shaft projecting rearwardly beyond the carriage, a winch-drum fast to said rear projection of the shaft, a second winch-drum occupying a position beyond the first drum's end limit of travel in one direction of the carriage's reciprocatory movement and journaled for rotation about a stationary axis paralleling the rotary axis of the first drum, means for braking said second drum at will, a pulley supported to occupy a position beyond the first drum's end limit of travel in the other direction of the carriage's reciprocatory movement, and an endless cable having multiple wraps taken about the second drum and passing therefrom to and about the pulley and in its return run having multiple wraps taken about the first drum, said winch-drums being each formed in their perimeter with a continuous spirally developed groove for guiding the cable in the latter's endwise movement upon the drum.

6. The power networks of claim 5 in which said pulley is carried by a block and with the block being journaled for slide movement on an axis paralleling the reciprocal path travelled by the carriage, means being provided subjecting said block to a spring load yieldingly urging the block directly from the drums.

7. As a power networks, and in combination with a reciprocally movable sawmill carriage having a master set-shaft journaled thereon for rotary movement about a transverse horizontal axis and providing transversely movable knees

6

powered from the set-shaft to cause the knees to be advanced and retracted by oppositely directed rotary movements of the set-shaft, said set-shaft projecting rearwardly beyond the carriage, a winch-drum fast to said rear projection of the shaft, a second rotatively mounted winch-drum located beyond the first drum's end limit of travel as the latter moves with the carriage in one direction of the latter's reciprocation and stationed to occupy a plane off-set from the horizontal plane occupied by the first drum, hydraulically actuated means for braking said second drum at will, a pulley stationed to lie in substantial horizontal alignment with the second drum beyond the first drum's end limit of movement in the other direction of reciprocal travel, and an endless cable having multiple wraps taken about the second drum and passing therefrom directly to and about the pulley and in its return having multiple wraps taken about the first drum but in a direction opposite to the direction in which the cable is wrapped about the second drum.
